UNITED STATES PATENT OFFICE.

WILLIAM RODIGER, OF CHICAGO, ILLINOIS.

INKSTAND.

No. 922,957.

Specification of Letters Patent.

Patented May 25, 1909.

Application filed July 5, 1907. Serial No. 382,184.

To all whom it may concern:

Be it known that I, WILLIAM RODIGER, a citizen of the United States, residing at the city of Chicago, in the county of Cook and State of Illinois, have invented a new and useful Improvement in Inkstands, of which the following is a specification.

This invention relates to an improvement in ink stands and particularly to that class of ink stands adapted for fountain pen fillers.

The invention consists in substantially the construction set forth in the subjoined specification, illustrated in the accompanying drawing and more particularly pointed out in the claim.

Like letters refer to similar parts in the several figures of the drawing, in which—

Figure 1 is a perspective view of the ink stand with the cover lifted. Fig. 2 is a vertical section of such ink stand on the line 1—1, Fig. 3, and Fig. 4 is a horizontal cross section on the line 2—2 of Fig. 2.

The reference sign A designates the body of the ink stand, which may be of any suitable material and the reference sign B designates the top or cover for the same, which should extend upward a sufficient distance to inclose whatever is contained within the body thereof, such, for instance, as the fountain pen filler, which latter is designated by the reference letter C. Within the body of the ink stand is arranged a removable ink well D, and this ink well is preferably formed of such a size and shape as to fill only a portion of the interior of such body portion of the ink stand and may be guided therein merely by the correspondence of its exterior shape to the interior shape of the body portion, or in addition be guided by interior lugs 40 a, which may be formed integrally with the body portion or detachably therefrom at the convenience of the constructor. The remaining space in the interior of the body portion is adapted to contain a wiper of any suitable material, and chamois is found convenient for that purpose, and a piece of chamois is indicated in the drawing by the letter b.

The ink well is adapted to receive the fountain pen filler, which latter is to be inserted therein for a portion of its length, and it has been found desirable in some instances to recess or rabbet the upper portion of such ink well so as to form a shoulder and provide the fountain pen filler with a flange d adapted to rest upon the shoulder, whereby the fountain pen filler is firmly supported in the ink well and yet capable of ready removal therefrom for use.

The ink stand may be made of any ornamental design and material, and contains within it not only the removable ink well, which latter may be removed to be filled and for cleaning, etc., but also has ample space in convenient approximation thereto for the piece of chamois or wiping material with which it is designed to wipe the fountain pen after it has been used. The ink well provides ample space for the ink and yet acts as a holder or support for the fountain pen filler while permitting it to be removed therefrom at will. There is thus arranged in one device the whole apparatus necessary for the proper and cleanly use of the fountain pen and the fountain pen filler in a most compact and convenient form.

What I claim and desire to secure by Letters Patent is—

As a new article of manufacture an ink stand inclosing in its interior an ink well and a fountain pen wiper in adjoining spaces, and the ink well having at its upper edge a shouldered recess, in combination with a fountain pen filler adapted to project within the ink well and having a flange to fit the shouldered recess of the same.

In testimony whereof I have signed my name to this specification, in the presence of two subscribing witnesses, on this 2nd day of July, A. D. 1907.

WILLIAM RODIGER.
